UNITED STATES PATENT OFFICE.

ARTHUR KING, OF MIDDLETOWN, PENNSYLVANIA, ASSIGNOR TO MIDDLE-TOWN CAR WORKS, OF MIDDLETOWN, PENNSYLVANIA, A CORPORATION OF PENNSYLVANIA.

DUMP-CAR.

SPECIFICATION forming part of Letters Patent No. 757,753, dated April 19, 1904.

Application filed October 15, 1903. Serial No. 177,151. (No model.)

To all whom it may concern:

Be it known that I, ARTHUR KING, a citizen of the United States, residing at Middletown, Pennsylvania, have invented a certain new and useful Improvement in Dump-Cars, of which the following is a full, clear, and exact description, such as will enable others skilled in the art to which it appertains to make and use the same, reference being had to the accompanying drawings, forming part of this specification, in which—

Figure 1 is a side elevational view of my improved dump-car. Fig. 2 is an end elevational view showing the body of the car in its tilted position in dotted lines. Fig. 3 is a vertical sectional view. Fig. 4 is a plan view of the truck. Fig. 5 is a view of some of the draft-rigging details, and Figs. 6 and 7 are modified forms of the longitudinal sills.

This invention relates to a new and useful improvement in dump-cars of that type wherein the body is tilted to one side to discharge the load.

The objects of my present invention are to construct a car of the character described, of steel, the several parts being so arranged and connected that a rigid structure results.

Another object is to provide an automatic lock for the discharge side of the body, to pivot the draft-rigging in position to facilitate the rounding of curves, and to bend the longitudinal sills of the body up at the ends to provide end posts.

With these objects in view the invention consists in the construction, arrangement, and combination of the several parts, all as will be hereinafter described, and pointed out in the claims.

In the drawings, 1 indicates the truck-frame, which is preferably made up of channels with their flanges presented outwardly, said channels forming the side members of the frame and being bent inwardly at the ends to form the end members, the contiguous ends of said end members being connected by splice-plates 2. Longitudinally-disposed angles 3 are connected to the end members of the frame to

stiffen the same and provide supports for the brake-beams, which are hung therefrom.

4 indicates a transversely-arranged angle 5° providing a cross-tie, said angle being attached to the longitudinal angles 3. The frame may be further strengthened by gusset-plates 5 at the corners thereof.

6 indicates the journal-boxes secured in position under the side member of the frame in which are mounted the axles of the supporting-wheels. While I have shown the truck-frame as being made of two pieces bent at the corners, it is obvious that said frame could be made of a single piece bent at the four corners, the ends being connected by a splice-plate, or, if desired, a square frame could be made up of separate pieces connected at the corners by connection plates or angles. 65

7 indicates a longitudinally-disposed draft member supported by the truck and extending beyond each end thereof. This draft member 7 is preferably in the form of an I-beam and carries platforms 8 at its ends, above 70 which may extend the usual hand brake-staff. The draft-rigging is suspended from the ends of this member 7 by means of stirrup-yokes 9 and 10, the former of which acts in the capacity of an ordinary carry-arm, the two uppermost members thereof being brought together on each side of the I-beam and bolted or riveted thereto. 75

11 indicates the draw-bar, having the usual shank which extends back over the draft-yokes and is surrounded by the usual draft-spring 12, operating between follower-plates 13 and 14, the follower-plate 13 bearing against the shoulder on the outer end of the tail-pin and the follower-plate 14 co-operating with the cross-key 15, passing through the inner end of the tail-pin. 80

16 indicates a bracket secured to the under side of the I-beam 7, which bracket forms a fulcrum-bearing for a swivel-stirrup 17, pivoted thereto by means of an appropriate pivot-bolt. This stirrup 17 embraces the ends of top and bottom yoke-pieces 18 and 19, whose shape is best shown in Fig. 5. It will be seen 90

in this construction that the top and bottom yoke members are substantially U-shaped, their connected ends being brought together and riveted, the bottom yoke being bent 5 downwardly and forwardly, as at *a*, to provide a support for the follower-plates. The outer ends of the follower-yokes extend upwardly and thence outwardly to provide points of attachment with the top yoke, the extreme 10 ends of the bottom yoke being bent upwardly in front of the ends of the top yoke, said ends being connected by a cross-bar 20. This draft-rigging frame is extremely simple in construction and cheap to manufacture, being 15 held in position by the supporting-stirrup 10, which permits lateral play of said frame resulting from the swivel-yoke connection with the bracket 16. Thus the draw-bar and shank are capable of movement to facilitate 20 the rounding of curves, and the draft-frame and springs move with the draw-bar.

22 indicates arched tie-braces whose ends are secured to the end members of the truck-frame, said tie members extending over the 25 I-beam 7 and riveted thereto for well-understood purposes.

23 indicates body-supporting knees which are preferably made up of angles and mounted upon the truck-frame. These knees carry 30 rotatable locking-pins 24, which are designed to coöperate with links 25 on the body, whereby when the body is in its normal position it may be locked in place.

27 indicates brackets depending from the 35 end members of the frame, which brackets are reinforced by flanged plates 28, said plates being preferably in vertical alinement with the longitudinal sills 3, to which their upper flanges are riveted. The brackets 27 carry a 40 track-plate 29, which is preferably arched, as shown, the tread portion of which is provided with rocker-engaging teeth 30 for well-understood purposes. The highest portion of this track-plate is preferably flat, and the 45 rocker 31, which rests thereon, is provided with a corresponding flat face, so that when the car-body is in an upright position these flat faces will overcome the tilting tendency in rounding curves. The rockers 31 are provided 50 with recesses to take in the teeth 30. While I have shown teeth on both sides of the track, it is obvious that only the teeth on the dumping side will ever be used in practice; but I prefer to extend the teeth throughout 55 the tread portion of the track in order that the same pattern of track may be used at either end of the car.

The rockers 31 have supporting-heads at their upper ends for the attachment of transverse sills 32, which are preferably in the form of inverted channels with a wooden filler-block. These sills 32 are arranged under the body of the car, which is constructed as follows:

33 indicates longitudinal sills, preferably in the form of Z-bars, which extend the entire length of the car-body and have their bottom flanges riveted to the transverse sills 32. At the ends of the car-body the bottom flanges of these sills are cut away, and the sills are 70 bent upwardly over said cut-away portions to form end supports 34. Instead of using Z-bars it is obvious that two angles could be employed, as shown in Fig. 6, or a channel, such as shown in Fig. 7, could be used. In the event 75 of the two angles being used the top angle could be bent up to form an end post, while the bottom angle could be cut off beyond the body-transoms. The bottom flange could be removed similar to the removal of the bottom 80 flange of the Z-bar. The top flanges of these sills and their extensions on the end supports form efficient supports for the ends and bottom of the car, which ends and bottom are preferably made in one piece, the sheet being 85 continuous.

The fixed side wall of the car-body is secured in position by means of an angle 35, riveted throughout its length through the end and floor sheet to the side sill member 33 and 90 its extension 34. To the vertical legs of this angle 35 is riveted the side sheet 36, whose upper end is reinforced by an exteriorly-arranged angle.

38 indicates hinged lugs which are riveted 95 to the extensions 34 of the side sills and from which the door 39 is swung. This door 39 is preferably made of one sheet, having a reinforcing-angle 40 at its lower edge and a similar angle 41 at its upper edge. The straps 100 42 of the hinges serve as reinforces for the ends of the door.

43 indicates hinged castings, of which there are preferably two, secured to and depending from the vertical web of the sill 33 on that side of the car upon which the door 39 is located. Locking-levers 44 are pivoted in the castings 43, the upper ends of said locking-levers being overbalanced and extending when the body is in normal position slightly above 110 the reinforcing-angle 40 of the door. The lower ends of these locking-levers extend down and coöperate with angle stop-plates 45 on the truck-frame.

The operation of the car is as follows: When 115 the car is to be loaded, the links 25 are engaged by the rotating members 24, which swing down by gravity and in this manner avoid accidental displacement. The locking-levers 44 are in position and hold the door 39 120 in place. After the car has been loaded it is moved to the place where it is desired to dump the load, when the links 25 are released and the body is tilted toward the side carrying the hinged door 39. As the body moves in the 125 direction shown by dotted lines in Fig. 2 the lower ends of the locking-levers are carried away from their stops 45, and the overbal-

anced upper ends of the levers move said levers away from the lower edge of the door 39, permitting said door to swing outwardly, so as to discharge the load. After the load is discharged the body is restored to normal position, and in this movement the overbalanced ends of the locking-levers permit the door 39 to swing home by gravity without interference, after which the final movement of the body to its home position causes the lower ends of the levers to engage their stop-locks and move the upper ends inwardly against the lower edge of the door 39. The links 25 can now be secured, and the car is ready to be again loaded.

While I have shown and described above a construction wherein the car is designed to be dumped only from one side, it is obvious that with slight changes the car can be made to dump on either side. In this event both side walls would be hinged to form side doors, and by the use of the rotatable locking-pins 24 and links 25, fastened to the truck-frame and car-body, respectively, the car would be held in normal position. Of course this construction would obviate the use of the body-supporting knees 23.

I am aware that minor changes in the construction, arrangement, and combination of the several parts of my device can be made and substituted for those herein shown and described without in the least departing from the nature and principle of my invention.

Having thus described the invention, what is claimed as new, and desired to be secured by Letters Patent, is—

1. In a car, the combination with a truck-frame composed of channeled side members with their flanges presented outwardly, said side members being bent to form the ends of the frame, a splice-plate to connect the bent ends, and a superposed draft member; substantially as described.

2. In a car, the combination with a truck-frame composed of channels with their flanges presented outwardly, the side members of said frame being bent to form the end sections of the frame, longitudinally-disposed tie-bars, cross tie-bars, and a superposed draft member; substantially as described.

3. In a car, the combination with a truck-frame, of superposed draft member, arched tie-braces, and connection-plates for securing said draft member to the truck-frame, plates forms on the ends of the draft member, and draft-rigging pivoted under the draft member; substantially as described.

4. In a car, the combination with a truck-frame, of an I-shaped draft member carried thereby and extending at each end beyond the truck-frame, stirrup-yokes suspended from the ends of the draft member, draw-bars carried by said stirrup-yokes, draft-springs, fol-

lower-plates, a bottom yoke bent to provide shoulders for the follower-plates, a top yoke 65 secured to the extremities of the bottom yoke, both of said yokes being substantially U-shaped, a cross-bar connecting the free ends of the yokes, a swivel-stirrup engaging the closed ends of the yokes, and a pivoted bracket 70 in which said swivel-stirrup is connected; substantially as described.

5. In a car, the combination with a truck-frame, of brackets depending from the end thereof, longitudinal sills for stiffening the 75 frame, and flanged web-stiffeners riveted to said brackets and to said longitudinal sills; substantially as described.

6. In a car, the combination with a truck-frame having longitudinal sills, of brackets 80 depending from the end thereof, track-plates supported by said brackets, and flanged plates 28 riveted to the brackets and to said sills; substantially as described.

7. In a car, the combination with transoms, 85 of Z-shaped sills connected thereto, the bottom flanges of said sills being removed and the ends bent up to form end posts; substantially as described.

8. In a car, the combination with body- 90 transoms, of sills having top and bottom flanges, the bottom flanges being discontinued a short distance beyond said transoms, and the remaining portion of the sills being bent up to form end posts; substantially as described. 95

9. In a dumping-car, the combination with a hinged side, of automatic locking-levers co-operating therewith, and means co-operating with said levers to positively lock the hinged side in its closed position; substantially as de- 100 scribed.

10. In a dumping-car, the combination with a truck-frame and a hinged side wall, of locking-levers co-operating therewith, and means co-operating with said levers to positively lock 105 the hinged side in its closed position; substantially as described.

11. In a dumping-car, the combination with a tilting body having a hinged side, of locking-levers carried by said tilting body and co-operating with said hinged side, and a truck-frame with which said locking-levers also co-operate to positively lock the hinged side in 110 its closed position; substantially as described.

12. In a dumping-car, the combination with a truck-frame, of a tilting body having a hinged side, overbalancing locking-levers co-operating with said hinged side, and means co-operating with said levers to positively lock 115 the hinged side in its closed position; substantially as described.

13. In a dumping-car, the combination with a truck-frame having stop-blocks, of a tilting body having overbalanced locking-levers mounted thereon, the lower ends of said levers 120 co-operating with said stop-blocks, whereby 125

they are positively operated when the body approaches its upright position, and a hinged side on the tilting body, with the free end of which the overbalanced upper ends of the locking-levers coöperate; substantially as described.

In testimony whereof I hereunto affix my

signature, in the presence of two witnesses, this 5th day of October, 1903.

ARTHUR KING.
